WILBUR H. ARMACOST, OF NEW YORK, N. Y., ASSIGNOR TO THE SUPERHEATER COMPANY, OF NEW YORK, N. Y.

WATER COOLED FURNACE

Application filed October 9, 1930. Serial No. 487,490.

My invention relates to water cooled furnaces and more particularly to those having surfaces on which the centers of the water tubes are spaced apart a sufficient distance so that slagging of the inner face of the refractory wall of the furnace would occur in the ordinary forms of construction, and aims to provide an arrangement whereby wide spacing of the tubes may be retained and the 10 slagging prevented.

In order that my invention may be fully understood, I will describe in detail, in connection with the attached drawing, one of several forms of boiler furnaces in which my 15 invention may be embodied. In said drawing,

Fig. 1 is a vertical sectional view through a boiler furnace having a wall section in accordance with my invention; Fig. 2 is a fragmentary elevation of a portion of the wall of the furnace shown in Fig. 1, and Fig. 3 is an enlarged sectional view on line 3—3 of Fig. 1.

Present-day boiler practice tends more and more to operation of the boilers at high ratings, with the result that higher and higher amounts of fuel per cubic foot of combustion space have been employed. At one time, the gradual increase in outputs of boilers and furnaces was stopped by the serious slagging 25 of the furnace refractories caused by particles of molten ash striking the face of the furnace wall. The difficulties with the refractories have been largely overcome by lining the furnace with water tubes whereby the 30 refractories are protected to a great extent from the furnace temperatures. On certain surfaces of boiler furnaces, however, it is desired to space the centers of the water tubes so far apart that, unless special precautions 35 are taken, slagging of the furnace refractories would occur in certain types of boiler furnaces now in use. For instance, it is convenient often to introduce pulverized fuel 40 into the boiler furnace through burner nozzles which project into the furnace through the walls thereof at points between the water tubes. This arrangement of the burners necessitates spacing the water tubes far 45 enough apart so that, when using pulverized fuel in accordance with most recent practice,

slagging of the furnace refractories is apt to occur. I have found, however, that the water tubes can be spaced far enough apart along the inner face of the furnace wall to permit introduction of burner nozzles for pulverized 55 fuel without material slagging of the refractory provided the water cooled surface is built out a sufficient distance from the wall of the furnace. The necessary thickness of water wall for this purpose depends upon the 60 fusing point of the ash of the coal, but with ash of an average fusing point the maximum thickness of the water wall perpendicular to the furnace wall is about twice the minimum width of the openings in the water wall 65 measured parallel to the furnace wall. Moreover, it will be understood that, while having special advantages in furnaces having burner nozzles projecting between adjacent water wall tubes, my invention is not limited to furnaces using pulverized or liquid fuel as it 70 may be desired at times to space the refractory protecting water tubes widely for other reasons.

Referring to the drawing, the installation 75 illustrated therein comprises a furnace chamber 10 having refractory lined walls 12, 12 which are protected from slagging by closely spaced water tubes 14 arranged in a single layer along the inner face of the refractory. 80 Over certain wall sections 12a of the furnace 10, however, it is desired to space the refractory protecting tubes so far apart that slagging would occur with only one layer of 85 tubes. As illustrated, along the wall section 12a the refractory-protecting water tubes 14a are spaced sufficiently far apart to permit the insertion therebetween of burner nozzles 16 for pulverized fuel. Under these conditions, the layer 14a of water tubes in juxtaposition 90 to the refractory are as far apart as the diameters of the tubes and will not prevent slagging when the furnace is operated at the maximum ratings adopted for most of the 95 recent boiler furnace installations when using average coal. To overcome this difficulty I prefer to make the anti-slagging means of two layers of water tubes 14a and 14b, each tube of one layer united at its ends to one of the other layers and to common throats 14c 100

through which the tubes 14a and 14b connect to headers 18 and 20. The tubes in the layer 14b extend inwardly into the furnace far enough from the surface of the refractory to shade the exposed surface of the refractory sufficiently to prevent it from substantial slagging even when the furnace 10 is being forced with pulverized fuel. As illustrated, the elements of tubes in layer 14b farthest from the refractory lie about twice as far from the refractory as the minimum open distance between adjacent tubes in layer 14a.

The arrangement illustrated and in which water tubes are connected in pairs to common throats is commonly referred to as a bifurcated arrangement. It will be understood that I do not limit myself to bifurcated tubes. Moreover, as illustrated, the tubes in layer 14b are arranged so that their projections on the surface of wall 12a coincide with the projections of the tubes of layer 14a on such wall, but I do not limit myself to such relative arrangement.

In Fig. 1, I have shown furnace chamber 10 as associated with a boiler 22 of a well known type, but it will be understood that the boiler is not a part of my invention.

I claim:

1. The combination of a furnace chamber having an arch portion at its upper end, an inner layer of protecting water tubes over said arch portion, and an outer layer of protecting tubes over said arch portion, the tubes of said inner layer being spaced apart a distance to cause slagging of the refractory when the furnace is operated at high ratings, the tubes in said outer layer having an arrangement such that the projected area of each such tube upon the refractory surface of the arch overlaps the projected area upon such surface of one of the tubes of the inner layer, each pair of said overlapping tubes being sufficiently close to adjacent pairs to shade the refractory surface to prevent slagging thereof at the maximum rating for which a furnace is designed but regularly spaced from adjacent pairs to permit a direct view of the surface of the refractory to the extent whereby a portion of the refractory surface of the arch may reach a temperature adapted to promote combustion in the furnace.

2. The combination of a furnace chamber having a wall having an arch portion at its upper end, a layer of closely spaced protecting water tubes over said wall below said arch, and a double layer of protecting water tubes over said arch portion, tubes of the inner layer over said arch portion being spaced apart a distance to cause slagging of the refractory when the furnace is operated at high ratings, the tubes in the second layer over said arch being spaced farther from the refractory surface than said first layer and having an arrangement such that the projected area of each such tube upon the refrac-

tory surface overlaps the projected area upon such surface of one of the tubes of the inner layer, each pair of said overlapping tubes being sufficiently close to adjacent pairs to shade the refractory surface to prevent slagging thereof at the maximum rating for which the furnace is designed and regularly spaced from adjacent pairs to permit a direct view of the surface of the refractory, whereby a portion of the refractory surface of the arch may reach a temperature adapted to promote combustion in the furnace.

3. The combination of a furnace chamber having a wall having an arch portion at its upper end alongside of which is a layer of protecting water tubes spaced apart a distance sufficient to cause slagging of the refractory when the furnace is operated at high ratings, a second layer of spaced water tubes farther from the refractory surface than said first layer and each tube of which has an arrangement such that its projected area on the refractory surface overlaps the projected area on such surface of one of the tubes of said first layer, each pair of said overlapping tubes being sufficiently close to adjacent pairs to shade the refractory surface to prevent slagging thereof at the maximum rating for which the furnace is designed but regularly spaced from adjacent pairs to permit a direct view of the surface of the refractory, and a burner arranged to deliver into said furnace between adjacent pairs of said overlapping tubes.

4. The combination as set forth in claim 1 together with a burner arranged to deliver into the furnace through the arch portion and between adjacent pairs of overlapping tubes.
